GALOSH

Ursula Lasley, Chicago, Ill., assignor of one-half
to Bert Halberstadt, New York, N. Y.

Application April 4, 1938, Serial No. 199,791

2 Claims. (Cl. 36—7.3)

This invention relates to overshoes or galoshes and finds particular utility in shoes of this type to be worn over women's footwear.

One of the well known objections on the part of women to the wearing of galoshes is the difficulty and nuisance of donning and removing them, with the attendant liability of soiling or injuring the fingers or finger nails.

It is a major object of my invention to provide a galosh constructed in a novel manner so as to reduce such objections to a minimum.

More specifically stated, it is an object of the invention to provide a galosh which is slit at the rear downwardly from the top to a point adjacent to the heel, so as to permit the side and front portions of the galosh to be folded outwardly and forwardly over the toe portion, thereby facilitating the entrance and removal of the shoe into and from such toe portion, after which the side and front portions may be drawn rearwardly and upwardly to normal position to completely enclose the foot.

Another object is to provide an improved galosh of this character which is particularly designed to be worn over ladies' shoes having high slender heels, commonly known as French heels, and in which a deep narrow heel pocket is provided, with the aforesaid slit extending down into the said heel pocket.

30 A further object is to provide an improved construction for quickly opening and closing the said slit, including a so-called "zipper" fastening device arranged and coacting in a novel relation with other parts adjacent to such slit, to prevent the entrance of water and moisture therethrough, and to guard the shoe and stocking against injury by said device.

Another object is to provide a galosh of the character described wherein, in the forward folding of the side and front portions thereof, the heel pocket is also spread and flexed forwardly to further facilitate the entrance of the wearer's shoe into the galosh, and in this connection it is an ancillary object, in the case of a galosh having a deep narrow heel pocket for French heels, to provide a rear slit which extends from the top of the galosh continuously down to a point near the bottom of said heel pocket so as to facilitate the spreading and forward folding of the side portions and the forward flexing of the heel pocket as above described.

Further objects and advantages will become apparent from the following detailed description of the preferred embodiment of the invention shown in the drawing, in which:

Figure 1 is a side view of a galosh embodying the features of the invention.

Fig. 2 is a rear elevation showing the vertical slit in a closed position.

Fig. 3 is a side view of the galosh with the sides folded outwardly and forwardly and the toe portion of a high-heeled shoe disposed within the toe pocket of the galosh.

Fig. 4 is a vertical sectional view on an enlarged scale taken through the longitudinal median line of the galosh in the position as shown in Fig. 3.

Fig. 5 is a rear view of the galosh as shown in Figs. 3 and 4.

Fig. 6 is a rear view of the galosh in partially opened condition and with the marginal edges of the slit turned outwardly to show the underlying construction.

Fig. 7 is a detailed sectional view on an enlarged scale taken along line 7—7 of Fig. 6.

Galoshes as heretofore customarily made are closed at the rear and have an opening at the front to permit of insertion and withdrawal of the wearer's foot and shoe. The difficulty of donning and removing this type of galosh lies mainly in the frictional resistance of the rear portion of the galosh to movement along the heel and counter portion of the shoe, this being aggravated in cases where the shoe has a rubber or rubber-tipped heel. In women's shoes, and particularly those having French heels, there is a prominent rearward bulge or convexity of the counter portion; and galoshes for this type of shoe should have a similar rearward bulge to fit about said counter portion, with restricted or forwardly sloping portions above and below such bulge to conform to the wearer's ankle and the French heel of the shoe, respectively, so as to present the optimum in fit and neatness in appearance. This construction, however, aggravates the difficulty, in the case of a front-opening galosh, of donning and removing it, since the said rearward bulge makes more difficult the insertion or withdrawal, to such an extent that frequently a woman pulls a slipper or low shoe off her foot in the attempt to remove the galosh.

According to my invention, the galosh is provided with a slit at its rear portion, preferably along a vertical median line, extending from the upper edge down to a point below said rearward bulge, and in the case of a galosh for a French-heeled shoe, the slit is preferably continued down well into the heel-pocket, thus providing an entrance at the rear of the galosh and eliminating the said frictional resistance to entrance and

withdrawal of the shoe. The construction also permits the side and front walls of the galosh to be folded downwardly about the toe portion thereof, and, in the case of a French-heel galosh, also permits spreading and forward flexing of the heel pocket, thereby further facilitating such entrance and withdrawal.

Referring to the drawing, wherein a preferred embodiment of the invention is disclosed for illustrative purposes, the galosh comprises generally a body having a toe portion 11, a relatively deep heel pocket 12, a convex or rearwardly bulging counter 13, and a top or ankle portion 14. Preferably, though not necessarily, the body is 15 completely closed at the front and sides, and, as indicated in Figs. 2 and 6, is provided at its rear side with a vertical slit 16 therethrough extending from the upper edge downwardly substantially along the median line of the rear wall 20 through the convex counter 13 and to a point adjacent the base of the heel pocket 12.

Attached to the inner wall of the galosh and extending adjacent to the marginal edges of the slit are parts 17 of a conventional slide fastening 25 device commonly known as a "zipper" fastener. These parts 17 are spaced inwardly from the edges of the slit and serve to draw said edges into abutment as the coacting slide 18 is moved upwardly. Close-fitting registered abutment of said 30 edges, as shown in Fig. 7, prevents the entrance of moisture and conceals the fastening device, rendering the galosh substantially waterproof and giving it a neat appearance when the slit is closed.

35 A web or tongue 19 may be secured to the inner wall of the galosh along one side of the slit to extend across the slit and underlie the fastening device when closed, as seen in Figs. 6 and 7. Such a tongue may be formed of any suitable 40 moisture-proof material and serves not only to obstruct the entrance of moisture but also as a guard-strip to protect the wearer's shoes and hose from injury by the fastening device. If desired, the lower portion of this guard strip, corresponding 45 for example to the depth of the heel pocket 12, may be fastened at both its side edges and its bottom edge to the wall of the galosh adjacent to the slit 16, as indicated at 19^a, 19^b and 19^c, respectively, in Fig. 6, so as to provide a 50 more effective seal against the penetration of moisture, and said lower portion may be made of material which is elastic in a direction transversely of the strip, allowing it to stretch to the extent necessary to permit the forward folding 55 of the side and front walls into the positions seen in Figs. 3, 4 and 5.

The walls of the galosh may be made of any flexible waterproof material as is customarily employed and may be lined with an insulating 60 fabric 20. As indicated in Fig. 7, the fabric lining attached to the inner wall of the galosh terminates a short distance from the slit 16 to accommodate the fastening elements 17 and guard strip 19, thereby reducing the over-all thickness 65 of the assembled layers in this zone. When the slide fastener is in closed position the tongue 19 lies in smooth, unfolded, substantially flat condition and the edges of the outer wall of the upper are drawn into abutting engagement so 70 that the fastener elements are completely concealed and a very neat appearance is effected. Preferably the tongue is fastened at one of its

vertical edges to the upper substantially throughout its entire length, and its opposite edge is unattached except at its lower portion. Thus the tongue does not interfere with the free opening and forward folding of the upper.

5 In donning or removing the galosh, the side and front portions thereof may, if desired, be folded outwardly and forwardly to a position enclosing the front or toe portion of the galosh, as shown in Figs. 3, 4 and 5. In this position the heel pocket is spread and flexed forwardly to provide the minimum obstruction to insertion of the shoe, as indicated in Fig. 3, after which the portions which are folded forwardly may be drawn up over the shoe and ankle. In so doing, 15 the heel pocket of the galosh is released for movement up and around the heel of the shoe. The slide 18 may then be moved upwardly to its closed position, drawing the marginal edges of the slit 20 into registered abutment and forming a neat fit over the heel, counter and ankle.

It will be apparent from the foregoing that my invention provides a novel and improved galosh, particularly well adapted to be worn over a woman's shoe having a high heel and a convex 25 or bulging counter, and which has advantages and novel features of construction permitting easy insertion and removal of the shoe, efficiently preventing the entrance of water and moisture therethrough, providing a neat fit and present- 30 ing an attractive and tidy appearance.

I claim as my invention:

1. A galosh having closed side and front portions and a deep heel pocket with a vertical slit 35 in the back extending from the top of the galosh to a point adjacent the bottom of said pocket, a slide fastener for closing said slit, and a resilient flap transversely stretchable and moisture-proof in its lower portion, spanning said slit and located inwardly of said fastener and secured 40 to the adjacent inner walls of said heel pocket along both of the side edges of the flap in such manner as to lie flat and unfolded across the inner side of said fastener, to exclude moisture and to form a smooth flat protecting strip preventing contact of the shoe and hose with the fastener when the latter is closed, said flap being unattached at one edge above said lower attached portion so as to permit the forward folding of the front and side portions of the galosh to facilitate ingress and egress of the wearer's shoe. 50

2. An overshoe including a body having a slit from the top to substantially the bottom thereof, a slide fastener device for closing said slit, and guard means on the inside of said body 55 to extend across said slit and underlie said slide fastener device for protecting the wearer's articles of dress such as shoes or hose within said body, said guard means including an upper portion attached to the body at only one side of said slit to permit opening of the slit and folding back of the body at each side of the slit to facilitate donning or removing the overshoe, and a lower elastic portion secured to said body at both sides of said slit and below the lower end of said slit in a manner to exclude entrance of moisture to the interior of said body but being yieldable to permit spreading of the lower end of said slit when said body is opened or folded back along said slit. 65
